APPARATUS FOR SEVERING SHEETS

Frederick O. Smith, Brooklyn, N. Y., assignor of
one-half to A. Stirling Smith, New York, N. Y.

Application July 7, 1933, Serial No. 679,289

5 Claims. (Cl. 164—60)

This invention is concerned with the production of single items of printed matter which are first printed in multiple layouts, that is, with a plurality of complete forms printed on a single sheet, and particularly those which have contrasting color or design effects at the edges which are originally joined. In practice heretofore, when it has been desired to secure the advantages of multiple layout printing, and to produce a booklet or the like, with a design having opposite edges of contrasting color, shade, or design, for example, one half red and one half white, there have been two alternatives open to the printer. He could use the cutter which is frequently built into a folding machine. If he did this, due to the limitations of human accuracy, he would find the cut going a little into the red, leaving a hair-line of red on the white edge, or vice versa. This spoils the effect of the design. His other alternative was to retrim the product in a separate operation, with consequent added expense and consumption of time. By the present invention, both edges can be trimmed perfectly and automatically in the folding machine. The solution offered by the present invention involves making the color portion and the adjoining plain portion in the multiple layout each a little wider than desired in the finished product, and cutting out a strip which includes the juncture and extends a little to each side of it, as shown in Figs. 4 and 5.

This may be absolutely necessary in order to cut perfectly clean edges in the one operation, as where in the finished product the north and south edges are contrasting and the east and west edges are also contrasting. Or it may be desirable where only two opposite edges are different from each other, but the exigencies of layout require that those two edges be joined in the multiple form.

It will often be more satisfactory to cut out a waste strip with two spaced cutters than to make a single cut even where the ends of the form do not contrast, because this allows more scope for adjusting measurements, and, also, if the form of cutter used leaves a clean cut at one side but a rumpled edge at the other, the waste strip can be the side to take the rumpled edge and no harm will be done.

The usual folding machine has one or more pairs of opposed circular knives included in it, for cutting up multiple forms as they pass through in the folding operation. The above described method of cutting apart the forms introduces the problem of how to handle the waste

strip. I have accordingly devised specific structure to handle it. This structure can be applied as an accessory to the conventional folding machine, its knives being reset or additional ones added as may be necessary. 5

Referring more particularly to the drawings: Fig. 1 is a vertical sectional view showing how the multiple forms pass through the cutters and the single forms pass onto a receiving belt, while the waste strips are deflected into a waste chute; 10

Fig. 2 is an elevational view on the broken line 2—2 of Fig. 1, showing the cutters and the guide for the cut-out strip;

Fig. 3 is a perspective view showing the guide to receive and discharge the narrow waste strip; 15

Fig. 4 is a perspective view showing a pair of printed forms made up together by multiple layout printing; and

Fig. 5 is a perspective view showing the pair of printed forms after being cut apart to their final single form, the cut-out strip also being seen here. 20

In the drawings, the multiple printed form A comes through folding rolls 1, 2, 3, and passes between spaced circular knives 4 and 5 mounted on shaft 6, and cooperating knives 7 and 8 mounted on shaft 9. These knives cut the form into two finished products B and C and a waste strip D, which waste strip D will include the juncture between parts C1 and B2 of contrasting color or design, when the form is so gotten up, thus leaving clean edges as explained above. 25

The finished forms B, C pass on to a belt conveyor 10 for further folding or for stacking.

The waste strips D are engaged by the projecting tongue 11' of a deflector 11 which curves 35 around the lower cutter shaft 9 and whose tongue extends into the path of travel of the paper fed through. This deflector is narrowed at its tip 11' to the smallest desired width of the waste strip, and widens at a point just below the path of the 40 paper, serving to catch the waste strips and guide them around and deposit them in a waste receptacle or trough 21. Where the deflector widens the shoulders 12, 13 are curled back so that the waste strips will not catch on them. The deflector at its lower end is bent back on itself to terminate in a socket 14 secured to a part of the frame of the machine as by a set screw 15. It can thus be fastened to the frame of the ordinary folding machine. 45

Between the deflector 11 and the lower cutter shaft 9, there is disposed a stripper 18 which, at the point where the cutting takes place, is within the periphery of the lower cutters 7 and 8. This stripper extends both forwardly and rearwardly, 55

curving out beyond the periphery of the knives, and thus acts to clear the waste strips from between the lower cutters.

The stripper 18 is supported by a generally rectangular bracket strap 16 which extends around both deflector 11 and stripper 18, each of those members being secured to the inside of the bracket strap. Thus, a clear unobstructed channel, of any desired width, is left for the waste strips to pass through, since the bracket-strap extends sideways first before traversing the distance between the deflector and stripper. The short sides 16' of the bracket-strap help guide the waste strips in that they prevent their falling or sliding 15 out to the side.

In a preferred embodiment, the stripper arrangement is made adjustable as to width. As shown in Fig. 3, tongue 17 has parallel rods 18, 19 affixed to its ends, and a second tongue 20 has 20 ends bent part way around these rods. Thus, this tongue 20 can be pushed directly over tongue 17 if the cut-out strip is to be narrow, as shown in full lines in Fig. 3, or can be slid to the side along rods 18, 19 if the strip is to be wider, as shown in 25 dotted lines in Fig. 3.

It is to be understood that I have described and illustrated a particular form of my invention, but the inventive concept can obviously be made use of in various embodiments, so I wish to be limited 30 only by the scope of the claims. Where I have referred to "printed matter", I means to use that expression generically, to include the products of lithography, embossing, and every other process by which paper, cloth, leather, fabric, metal foil, or 35 the like may have dissimilarities in appearance imparted to parts of its surface.

It is to be understood also that apparatus of my invention may be installed on a press, so that as the printed product comes out of the press, it 40 will pass through my cutters. Such installation could be made on any press, as, for example, web, newspaper, gravure, and lithographic presses, in addition to the ordinary printing press. The cutters could be driven from the same power source 45 as the press and in unison therewith.

I claim:

1. A sheet cutter comprising two laterally spaced pairs of opposed cutting knives, mounted on shafts, through which the sheets are fed, a deflector at the rear side of the knives starting above the path of the sheets and extending therebelow and being positioned opposite the space between the knives, a stripper between the deflector and the lower knife shaft and extending both forward and backward from the point of severance, a bracket-strap fastening said stripper and deflector together, said bracket-strap extending sideways from the stripper and from the deflector before bridging across. 5

2. The device of claim 1 in which parallel rods extend laterally from the ends of the stripper, 15 and a second stripper member is slidably mounted on said rods.

3. The device of claim 1 in which parallel rods extend laterally from the ends of the stripper, 20 whereon is slidably mounted a second stripper member of substantially the same size and shape as the first, whose ends are curled part way around said rods, so that it may be positioned directly over the first stripper or spaced out to the 25 side thereof.

4. An attachment for a sheet cutting and folding machine, adapted to separate out and guide away an intra-marginal strip cut out of a sheet by spaced cutters, consisting of a deflector having its lower end shaped to form a fastener for attachment to the machine, and its upper end extending as a narrow tongue for engaging and guiding the cut-out strip, a stripper spaced from 30 said deflector, and a bracket-strap extending around the outside of both deflector and stripper 35 and attached to both to secure them together.

5. The device of claim 4 in which parallel rods extend laterally from the ends of the stripper, 40 whereon is slidably mounted a second stripper member of substantially the same size and shape as the first, whose ends are curled part way around said rods, so that it may be positioned directly over the first stripper or spaced out to the side thereof.

FREDERICK O. SMITH. 45
